UNITED STATES PATENT OFFICE.

JOHN WILLIAM BARNARD, OF SHANNON, NORTH CAROLINA.

DESIGN FOR A PLOW-STOCK.

SPECIFICATION forming part of Design No. 27,918, dated November 30, 1897.

Application filed September 22, 1897. Serial No. 852,662. Term of patent 7 years.

To all whom it may concern:

Be it known that I, JOHN WILLIAM BARNARD, a citizen of the United States, residing at Shannon, in the county of Robeson and State of North Carolina, have invented and produced a new and original Design for a Plow-Stock, of which the following is a specification, reference being had to the accompanying drawing, forming a part thereof, which represents a perspective view of a plow-stock embodying the features of my design.

The design consists in the stock proper, comprising an upright section A, terminating at its upper end in a fork, the members whereof are designated as a and a' , and a lower horizontal section B, connecting with and virtually constituting a continuation of the upright section A. The horizontal section B represents a landside, and in the side surface of the horizontal member B of the stock a longitudinal depression D appears.

The design further consists in the formation of the upper members of the fork, in which the member a of the fork terminates in a horizontal flange b , and an opening b' is shown in this member adjacent to the flange, while in the opposing member a' of the stock a vertical slot b^2 is apparently made.

A shoe C is formed at the outer or free end of the horizontal section B of the shank, the front face of the shoe being concaved. The shoe projects beyond the side of the stock opposite that in which the depression D is shown.

I claim—

The design for the plow-stock herein shown and described.

JOHN WILLIAM BARNARD.
